UNITED STATES PATENT OFFICE

2,095,121

HEATER PLUG WITH ROCKER SWITCH

George B. Benander, Bridgeport, Conn., assignor,
by mesne assignments, to Monowatt Electric
Corporation, a corporation of Connecticut

Application December 28, 1933, Serial No. 704,290

17 Claims. (Cl. 200—51)

This invention relates generally to switching mechanisms and is directed more particularly to the provision of a more reliable construction for switches of the oscillating type.

5 In switches of this type the switch arm is ordinarily mounted with its pivotal axis outside of the strap on the closed circuit side of the switch rather than between this strap and the strap on the open circuit side of the switch. When the 10 switch arm is thus mounted with relation to these straps, the closed circuit strap is extended along the interior of the switch body beneath the switch arm. Where the closed circuit strap and the switch are disposed within the switch body in the 15 relation mentioned, the switch arm, when actuated, rotates above a portion of the strap on the closed circuit side of the switch with the result that sparking sometimes takes place between the movable arm and the closed circuit strap.

20 It is an object of the present invention to eliminate in switches of the oscillating type the sparking which takes place, between the movable switch arm and the closed circuit strap of the switch. This is effected by mounting the switch arm with 25 its pivotal axis between the strap on the closed side and the strap on the open circuit side of the switch. Other objects of the invention will be evident upon reference to the following description of a preferred embodiment of the invention, and to the accompanying drawing, in which:

30 Fig. 1 is a perspective view showing the interior of the switch; Fig. 2 is a plan view, partly in section, showing details of the mounting of the circuit controlling assembly; and Fig. 3 is an 35 elevation of Fig. 2, partly in section.

Referring now to the drawing, a switch body 1, constructed of suitable insulating material, is adapted, when joined with the usual complementary switch body (not shown), to form a switch 40 enclosure. The switch bodies comprising this enclosure are fastened together in the usual manner, that is, by screws or bolts (not shown) extending through openings in the switch bodies. When an opening 2, at one end of the switch body 1, is positioned opposite a complementary opening in the other body (not shown) of the switch enclosure, the two openings form an aperture through which conductors (not shown) can be introduced and connected to the inlet binding 45 screws 3 and 4. Disposed within similar longitudinal recesses at that end of the body, which is opposite the opening 2, are the usual spring outlet terminals 5 and 6. These terminals may be connected to the input terminals of an electric heater, electric iron, etc. It is to be under-

stood however that the spring terminals 5 and 6 may be replaced by binding posts, etc., to which conductors connected to any electricity consuming device may be attached, without departing from the scope of the present invention.

On the open circuit side of the switch and extending between the spring terminal 5 and the binding screw 3 is a strap having two sections 7 and 8 terminating in spaced contacts 9. The section 7 is riveted to an arm of the spring terminal 5 and is disposed within a recess in the body 1. Both the spring terminal 5 and the section 7 of the strap are fastened to the body 1 by a screw 10 which threads into an opening in the body. The section 8 of the strap is disposed within a recess in the body 1 and is jointly fastened to the body by the binding screw 3 and another screw 11, which are threaded into openings in the body. On the closed circuit side of the switch and extending between the spring terminal 6 and the binding screw 4 is the strap 12 which is riveted to an arm of the spring terminal 6. This spring terminal and one end of the strap 12 are fastened to the body 1 by a screw 13 threaded into an opening in the body. The other end of the strap 15 is fastened to the body by the binding screw 4 and another screw (not shown) corresponding to 20 11, which are also threaded into openings in the body. 25

A switch lever 14, constructed of suitable insulating material, is provided with a knurled edge 15 and with an opening 16 by means of which the switch lever is pivoted on the extension 17 of the strap 12. When thus pivoted, the switch lever extends into the central portion of the body 1 through an opening in the side wall, formed by 30 complementary openings in the two switch bodies, and through an opening formed by the legs of the strap 12. In the opening 16 of the switch lever is a triangular projection 18 (Figs. 1 and 2). The apex of this projection bears against the extension 17, thus permitting the switch lever to be oscillated in either direction until the sides of the projection engage the extension 17, limiting the movement.

45 A switch arm 19, which serves to connect and disconnect the spaced contacts 9, is pivotally mounted with its pivotal axis or axis of rotation between the closed circuit strap 12 and the open circuit strap comprising the sections 7 and 8. 50 To effect this mounting, the strap 12 is formed to hold a bracket 20, constructed of suitable insulating material, and the arm 19 is provided with bearings including an opening in the bracket 20 and an opening in the body 1. To enable the 55

bracket 20 to be attached to the strap 12, the latter is provided with a portion 21 forming a surface substantially perpendicular to the lengthwise surface of the strap, with an opening 22 and with two lugs 23 (Fig. 2), each positioned at one side of the opening 22 (only one lug being shown in Fig. 2) and each extending inwardly from the interior surface of the strap. The bracket 20 is wedged into the opening 22 between the lugs 23, and underneath the portion 21 of the strap. In addition, the bracket may be cemented or otherwise fastened to the strap in order to hold it more securely thereto.

Although the switch arm 19 is mounted on bearings in the body 1 and the bracket 20, in the embodiment of the invention set forth herein, and is thus mounted only in part on the strap 12, it is evident that a second bracket, similar to 20, might be attached to this strap and the switch arm 19 provided with bearings in the two brackets, thereby mounting the arm entirely on the strap. It is likewise evident that the switch lever 14, instead of being supported on the body 1, may be supported entirely by, or mounted entirely on, the strap 12. These modifications of the invention, as well as others that will be readily suggested to those skilled in the art, are to be understood as falling within the scope of the present invention.

30 A spring 24, attached to the switch arm 19 and the switch lever 14, serves to actuate the switch arm upon the movement of the switch lever. One end of this spring is attached to a V-shaped re-entrant portion 25 of the switch arm 19 and the other end is fastened in an opening provided in an arm 26 of the switch lever 14.

The operation of the switch will now be briefly described. When the switch arm 19 is out of engagement with the spaced contacts 8, and the 40 switch lever 14 is moved to the left, the triangular projection 18, being fulcrumed at the extension 17 of the strap 12, causes the spring 24 to be compressed until the switch lever is rotated beyond the line of action of the spring. When this 45 occurs, the spring 24 suddenly releases, oscillating the switch arm 19 into engagement with the spaced contacts 8, whereupon the arm is brought to a halt by the engagement of a side of the projection 18 with the face of the extension 17. The two sections 7 and 8 of the strap are thus electrically connected by the switch arm 19. The oscillation of the switch arm 19 out of engagement with the contacts 8 is effected in response to the movement of the switch lever 14 to 55 the right and the travel of the arm away from the contacts is terminated when the other side of the projection 18 meets the surface of the extension 17.

The present invention provides a switch having 60 its switch arm pivotally mounted with its pivotal axis between the straps on the closed and open circuit sides of the switch. This method of mounting the switch arm eliminates the sparking, which takes place between the closed circuit 65 strap and the movable switch arm in switches having the switch arm pivotally mounted with its pivotal axis elsewhere than between the straps on the open and closed circuit sides of the switch. The invention accordingly provides a more reliable switch construction for switches having a 70 circuit controlling assembly.

The invention is not to be restricted to the particular form or arrangement of parts shown and described herein, since they may be changed and modified in a manner obvious to those skilled 75

in the art without departing from the scope of the invention.

What I claim as new and desire to secure by Letters Patent of the United States is:

1. In a switching device, a switch body of insulating material, a current inlet terminal and a current outlet terminal, a first strap connected between said terminals, another current inlet terminal and another current outlet terminal, a second strap comprising two normally disconnected sections connected between said other terminals, an extension on, and a bracket of insulating material attached to, the first strap, a switch lever of insulating material pivoted on said extension, and a contact closing member 5 mounted jointly on said body and bracket and actuated by the switch lever for connecting and disconnecting the sections of the second strap.

2. In a switching device, a switch body of insulating material, a current inlet terminal and a current outlet terminal, a first strap connected between said terminals, another current inlet terminal and another current outlet terminal, a second strap comprising two normally disconnected sections, connected between said other 25 terminals, an extension on and a bracket of insulating material attached to the first strap, a switch lever of insulating material pivoted on said extension, an arm having bearings in said switch body and said bracket, and a spring attached to 30 said arm and lever and controlled by said lever for rotating the arm into and out of engagement with the sections of the second strap.

3. In a switching device, a switch body of insulating material, a first strap extending between 35 a current inlet terminal and a current outlet terminal secured to the body, a second strap comprising two disconnected sections extending between another current inlet terminal and another current outlet terminal also secured to the body, 40 a switch arm for connecting and disconnecting the sections of the second strap, means for pivotally mounting the switch arm with its pivotal axis in a plane between the straps, and a switch lever of insulating material for actuating the 44 switch arm about its pivotal axis, said switch lever extending across the first strap and having a portion which projects outside the switch body.

4. In a switching device, a switch body of insulating material, a first strap spaced from the body and extending between a current inlet terminal and a current outlet terminal secured to the body, a second strap comprising two disconnected sections extending between another current inlet terminal and another current outlet terminal also secured to the body, a switch arm for connecting and disconnecting the sections of the second strap, means for pivotally mounting the switch arm with its pivotal axis in a plane 6 between the straps, a switch lever of insulating material pivotally mounted in the space between the first strap and the switch body, said switch lever extending across the first strap and having a portion which projects outside the switch body, and a spring connecting the switch lever and arm for actuating the arm upon the movement of the lever.

5. In a switching device, a switch body of insulating material, a first strap extending between a current inlet terminal and a current outlet terminal secured to the body, a second strap comprising two disconnected sections extending between another current inlet terminal and another current outlet terminal also secured to 1

- the body, a switch arm for connecting and disconnecting the sections of the second strap, means including at least one bracket of insulating material attached to the first strap for pivotally mounting the switch arm with its pivotal axis in a plane between the straps, and means for actuating the switch arm about its pivotal axis.
6. In a switching device, a switch body of insulating material, a first strap spaced from the body and extending between a current inlet terminal and a current outlet terminal secured to the body, a second strap comprising two disconnected sections extending between another current inlet terminal and another current outlet terminal also secured to the body, a switch arm for connecting and disconnecting the sections of the second strap, means including at least one bracket of insulating material attached to the first strap for pivotally mounting the switch arm with its pivotal axis in a plane between the straps, a switch lever pivotally mounted in the space between the first strap and the switch body and a spring connecting the switch lever and arm for actuating the arm upon the movement of the lever.
7. In a switching device, a switch body of insulating material, a first strap extending between a current inlet terminal and a current outlet terminal secured to the body, a second strap comprising two disconnected sections extending between another current inlet terminal and another current outlet terminal also secured to the body, a bracket of insulating material attached to the first strap, a switch arm having bearings in the bracket and the switch body and its axis of rotation between said straps for connecting and disconnecting the sections of the second strap, and means for actuating the switch arm about its pivotal axis.
8. In a switching device, a switch body of insulating material, a first strap spaced from the body and extending between a current inlet terminal and a current outlet terminal secured to the body, a second strap comprising two disconnected sections extending between another current inlet terminal and another current outlet terminal also secured to the body, a bracket of insulating material attached to the first strap, a switch arm having bearings in the bracket and the switch body and its axis of rotation between said straps for connecting and disconnecting the sections of the second strap, a switch lever pivotally mounted in the space between the first strap and the switch body, and a spring connecting the switch lever and arm for actuating the arm upon the movement of the lever.
9. An electrical attachment fitting of the character described, comprising a pair of mating housing parts, means for attaching said parts together, said housing parts being provided with prong receiving openings at one end, spring contacts within said openings attached to one of the housing parts for engagement with prongs inserted into said openings, a pair of binding screws within said housing, a switch within said housing, and current carrying parts associated with said binding screws, spring contacts and switch, said binding screws and current carrying parts being mounted on said one of said housing parts, said current carrying parts including a metal member parallel to said one of said housing parts, and said switch including a switch lever received between and mounted for swinging movement on said one of said housing parts and said metallic member.
10. In a switch device, a switch body of insulating material, a current inlet terminal and a current outlet terminal, a strap connected between said terminals, another current inlet terminal and another current outlet terminal, a second strap comprising two normally disconnected sections connected between said other terminals, said terminals and said straps being secured to said switch body and a portion of one of said straps being spaced therefrom, and a switch for connecting and disconnecting the sections of the second strap, said switch including a member mounted on and received between the spaced portion of said strap and said switch body.
11. In a switch device, a switch body of insulating material, a current inlet terminal and a current outlet terminal, a strap connected between said terminals, another current inlet terminal and another current outlet terminal, a second strap comprising two normally disconnected sections connected between said other terminals, said terminals and said straps being secured to said switch body and a portion of one of said straps being spaced therefrom, and a switch for connecting and disconnecting the sections of the second strap, said switch being supported by the switch body and having a part received between and mounted for swinging movement on said switch body and said portion of the strap spaced therefrom.
12. In a switch device, a switch body of insulating material, a pair of current inlet terminals at one side of the switch body, a pair of current outlet terminals at the other side of the switch body, a pair of laterally spaced straps respectively connected between one of the current inlet terminals and one of the current outlet terminals, one of said straps comprising two normally disconnected sections, said terminals and said straps being secured to said switch body and a portion of one of said straps being spaced therefrom, a switch arm for connecting and disconnecting said sections, means for pivotally mounting the switch arm with its pivotal axis perpendicular to the plane of the straps and in a plane between the straps, and a switch lever for actuating the switch arm about its pivotal axis, said switch lever extending across one of said straps and having a portion which projects outside the switch body.
13. In a switch device, a switch body of insulating material, a pair of current inlet terminals at one side of the switch body, a pair of current outlet terminals at the other side of the switch body, a pair of laterally spaced straps respectively connected between one of the current inlet terminals and one of the current outlet terminals, one of said straps comprising two normally disconnected sections, said terminals and said straps being secured to said switch body and a portion of one of said straps being spaced therefrom, a switch arm for connecting and disconnecting said sections, means for pivotally mounting the switch arm with its pivotal axis perpendicular to the plane of the straps and in a plane between the straps, a switch lever pivotally mounted on and received between said switch body and the portion of said strap spaced therefrom, said switch lever extending across said portion and having a part which projects outside the switch body, and a spring connecting the switch lever and arm for actuating the arm upon movement of the lever.
14. In a switch device, a switch body of insulating material, a pair of current inlet terminals

at one side of the switch body, a pair of current outlet terminals at the other side of the switch body, a pair of laterally spaced straps respectively connected between one of the current inlet terminals and one of the current outlet terminals, one of said straps comprising two normally disconnected sections having the ends thereof spaced from and parallel to each other, said terminals and said straps being secured to said switch body and a portion of one of said straps being spaced therefrom, a switch arm adapted to move between said ends and connect said sections, means for pivotally mounting the switch arm with its pivotal axis perpendicular to the plane of the straps and in a plane between the straps, and a switch lever for actuating the switch arm about its pivotal axis, said switch lever extending across one of said straps and having a portion which projects outside the switch body.

15. In a switch device, a switch body, a part projecting from said body having flat surfaces, a handle having an opening therein fitting over said part whereby it is pivoted thereon, a switch blade operated by said handle, and angular projections on the handle within the opening cooperating with said surfaces to provide stops limiting the pivotal movement of the handle.

16. In a switch device, a switch body, a flat metal part secured to said body and projecting therefrom, a handle having an opening therein through which said part extends whereby the handle is pivoted thereon, said part having portions projecting outside said opening whereby the handle is held thereon, a switch blade operated by said handle, and angular projections on the handle within the opening cooperating with the flat surfaces of said part to provide stops for limiting the pivotal movement of the handle.

17. In a switch device, a switch body, a flat metal part secured to said body and projecting therefrom, a handle having an opening therein through which said part extends whereby it is pivoted thereon, a flange extending angularly from the projecting end of said part, a switch blade pivoted on said flange, a spring connecting the handle and switch blade for actuating the blade upon movement of the handle, and angular projections on the handle within the opening for cooperating with the flat surfaces of said part to provide stops for limiting the pivotal movement of the handle.

25

GEORGE B. BENANDER.
